CLYDE C. TERRY, OF SEATTLE, WASHINGTON.

FRAMING FOR INTERNAL-COMBUSTION ENGINES.

1,284,489.

Specification of Letters Patent. Patented Nov. 12, 1918.

Application filed June 12, 1916, Serial No. 103,272. Renewed April 29, 1918. Serial No. 231,537.

To all whom it may concern:

Be it known that I, CLYDE C. TERRY, a citizen of the United States, residing at Seattle, in the county of King and State of Washington, have invented a new and useful Improvement in Framings for Internal-Combustion Engines, of which the following is a specification.

My invention relates to all types of internal combustion engines; and the objects of my improvement are, first, to insure perfect alinement of the cylinders with the cross-head-guides and cranks under all conditions of expansion, imposed upon the cylinders by the heat generated by combustion of fuel within them, thereby reducing friction, enabling a closer fitting of the piston to its cylinder and a closer adjustment of the bearings, and making possible a more accurate 20 and rigid construction throughout the entire engine; and second, to prevent stresses set up by unequal expansion of the cylinders, the tie-beams and the bed-plate, thereby reducing the weight of metal necessary to 25 these parts.

I attain these objects by the mechanism illustrated in the accompanying drawings in which Figure 1 is an elevation showing a pair of cylinders, a tie-beam and a part of the bed-plate, with the columns connecting the above named parts; Fig. 2 an end elevation showing a section through the hollow longitudinal girders of the bed-plate, a section through the hollow longitudinal tie-beam which spaces the columns and supports the guides, and a section through the cylinder block at the point at which the columns pass through it; and Fig. 3 a plan showing the cylinder beams and the columns fastened 40 to them.

Similar letters and similar figures refer to similar parts throughout the several views.

In this specification the words "longitudinal tie-beam" and "longitudinal girder" shall mean that said tie-beam or said girder lie parallel to the crank-shaft of the engine.

At 5 are shown two or more cylinders, each rigidly fastened, near its upper end to a pair of beams 8, by means of beams 12, 50 which beams 8 and 12 are all so constructed so as to allow a free circulation of cylinder cooling water around them. The aforesaid pair of beams 8 are rigidly fastened to several columns 1 at the upper extremity of 55 these said columns 1. From the columns 1, through the said beams 8 and 12, are hung

the cylinders 5 and the water-jacket 9. At point P where the said columns 1 pass through the bottom wall 3 of the water-jacket 9 bushing and packing glands are 60 provided thus positively spacing the cylinder and columns at this point and allowing free expansion in the direction of the dimension X'Y.

At 4 is shown a hollow longitudinal tie-beam fastened rigidly to several of the columns 1 and supporting the crosshead-guides shown at 10.

At 7 are shown two or more hollow longitudinal girders fastened rigidly to the cross-girders shown at 14, to which cross-girders are rigidly fastened the lower ends of the several columns 1, and between which cross-girders the crank-shaft of the engine revolves.

Both hollow longitudinal tie-beam 4 and hollow longitudinal girders 7 are provided with means for circulating water, of the same temperature as the water in the water-jacket 9 throughout their entire length.

The cross-head guides shown at 10 are rigidly supported from the columns 1 through single tie-beams 15 and the aforesaid longitudinal tie-beam 4.

Now, cylinders 5, cross-head guides 10, 85 and cross-girders 14, being fastened rigidly to, and held in alinement by, the several columns 1, and said several columns being positively and rigidly spaced, at the top by beams 8, at the point P by bottom wall 3, at 90 the point J by tie-beam 4, and at the bottom by girders 7, and being spaced by these aforesaid parts only, it follows that perfect alinement will be maintained by affording equal expansion to beams 8, bottom wall 3, 95 tie-beam 4 and girders 7.

As the internal combustion engine commences to operate the water contained in water jacket 9 is heated. Beams 8 being surrounded by, and bottom wall 3 being covered by the water contained in said water jacket, these two said members expand to a degree corresponding to the temperature of this water. At the same time, water of an equal temperature being circulated through 105 tie-beam 4 and girders 7, by means of pipes 17 and 18, these two members expand equally with beams 8 and bottom wall 3, thus maintaining perfect alinement between the cylinders 5, the crosshead guide 10 and the crank-shaft which revolves between the cross-girders 14.

I claim:

1. In internal combustion engines, hollow longitudinal tie beams provided with water circulation and hollow longitudinal girders provided with water circulation, both forming part of framing supporting two or more cylinders and two or more crosshead guides in which framing the said cross head guides are maintained parallel to each other and in line with the said cylinders by means of the equal expansion imposed upon the said hollow longitudinal tie beams and the said hollow longitudinal girders by the heat from the water circulated within them.
2. In internal combustion engines the combination of two or more cylinders, two or more beams each rigidly fastened to two or more of the said cylinders at a point near the upper extremity of same, a water jacket

surrounding said cylinders and said beams, 20 several columns rigidly fastened to the aforesaid beams and positively guided through the bottom wall of the said water jacket, one or more hollow tie beams each provided with a means to circulate water 25 within it said hollow tie beam or tie beams being rigidly fastened to several of the said columns, two or more cross head guides each rigidly supported by said tie beam or tie beams, two or more hollow girders each provided with a means to circulate water within 30 it, and several cross girders each rigidly fastened to the said hollow girders and to the bottom of two or more of the said columns, all substantially as and for the purposes set forth. 35

CLYDE C. TERRY.
